UNITED STATES PATENT OFFICE

JEROME A. WAGNER, OF SIDNEY, OHIO, ASSIGNOR TO THE WAGNER MANUFACTURING COMPANY, OF SIDNEY, OHIO, A CORPORATION OF OHIO

DESIGN FOR A SANDWICH TOASTER

Application filed July 15, 1932. Serial No. 44,347. Term of patent 7 years.

To all whom it may concern:

Be it known that I, JEROME A. WAGNER, a citizen of the United States, residing in the city of Sidney, in the county of Shelby and State of Ohio, have invented a new, original, and ornamental Design for a Sandwich Toaster, of which the following is a specification, reference being had to the accompanying drawing, forming part hereof.

The figure is a perspective view of a sandwich toaster, showing my new design.

I claim:

The ornamental design for a sandwich toaster, as shown.

JEROME A. WAGNER.
